(57) **CLAIM**

The ornamental design for an automotive wheel, as shown and described.

DESCRIPTION

FIG. 1 is a perspective view of an automotive wheel showing my new design; and,

FIG. 2 is a front elevational view thereof.

The broken line showing of the rear portion of the rim is included for the purpose of illustrating environment and forms no part of the claimed design.

1 Claim, 2 Drawing Sheets

FIG.1

FIG.2
